(57) CLAIM

The ornamental design for an upper heat grill, as shown and described.

DESCRIPTION

FIG. 1 is a top view of a upper heat grill showing my new design;

FIG. 2 is a left side view thereof;

FIG. 3 is a front view thereof; and,

FIG. 4 is perspective view thereof.

The broken lines in the drawings are included for the purpose of illustrating portions of the upper heat grill that form no part of the claimed design.
